SPOOL HOLDER

Filed Sept. 9, 1929

UNITED STATES PATENT OFFICE

ELSIE CATLETT, OF SOUTH JACKSONVILLE, FLORIDA, ASSIGNOR OF ONE-HALF TO
LINDSEY GILFILLAN, OF JACKSONVILLE, FLORIDA

SPOOL HOLDER

Application filed September 9, 1929, Serial No. 391,461.

This invention relates to thread holders and more particularly to a device of this character of a portable type which is adapted to be securely mounted and clamped on any convenient support and which is further adapted to support a plurality of spools of thread and which will occupy a very small amount of space, when in use.

An object of the invention is to provide, in a manner as hereinafter set forth, a spool holder of the aforementioned character, which is adapted to support a single large ball of worsted or yarn which may be too large to be mounted on the device in the same manner in which a conventional spool of thread is mounted thereon.

Other objects of the invention are to provide, in a manner as hereinafter set forth, a spool holder of the above mentioned character which will be simple in construction, strong, durable, efficient in its use, and which may be manufactured at a low cost.

Other objects of the invention will become apparent from a study of the following specification, taken in connection with the accompanying drawings, wherein like characters of reference designate corresponding parts throughout the several views, and wherein:

Figure 1 is a side elevation of a spool holder constructed in accordance with this invention.

Figure 2 is a front elevation of the same showing the large ball of yarn or worsted mounted thereon.

Figure 3 is a perspective view showing the device in use for holding a plurality of thread spools.

Referring to the drawings in detail, the reference character 1 designates a substantially inverted U-shaped supporting clamp having one end provided with a forwardly projecting loop 2 and at its opposite end with a clamping screw 3, and it is provided on one end with an actuating handle or knob 4 and on its opposite end is provided with a swivelled cushion head 5. It will be understood that the U-shaped clamp 1 is adapted to be slipped over any suitable support and clamped thereon by threading the screw 3 in-

wardly against said support. On the forward wall of the clamp 1 and above the clip portion 2 thereof is a hollow vertical rib or protuberance 6, having an open upper end. A plurality of vertically extending outwardly bent resilient wire rods 7 have their lower ends inserted in the portion 6, the rods 7 diverging upwardly from their point of connection with the clamp 1, and being provided at their upper ends with outwardly directed portions 8.

It is to be understood that the rods 7 may be secured at the lower end to the forward wall of the clamp 1, in any suitable manner, as by riveting, stapling or by soldering the same thereto. A ring 9 encircles all of the resilient spring rods 7 and when the device is in use for supporting a plurality of spools as illustrated in Figure 3 of the drawings, said ring is slipped downwardly on the rods 7 to a point adjacent the clamp 1 and the rods are thus allowed to spring outwardly to their normal positions. When the device is not in use, the ring 9 is slipped upwardly toward the upper end of the rod and the same are thus drawn together, as clearly shown in Figure 1 of the drawings.

Should it be desired to support a large ball of yarn or any other ball of cord or worsted having an enlarged opening therethrough, this may be accomplished by drawing the rods together, as in Figure 1, slipping the ball of yarn or worsted over the upper hooked end of the same and then sliding the ring downwardly, thus permitting the rods to expand and press the hooks 8 into the side walls of the openings through the ball of yarn or worsted.

It is believed that the many advantages of a spool holder constructed in accordance with this invention will be readily understood and although the preferred embodiment of the invention is illustrated and described, it is to be understood that changes in the details of construction may be had, which will fall within the scope of the invention as claimed.

What is claimed is:

1. A spool holder of the character described, comprising a clamp, a plurality of diverging resilient wires mounted on said

clamp, each of said wires being adapted to support a plurality of spools, and a slidable ring encircling said wires and adapted to draw the diverse ends thereof together when moved upwardly thereon.

2. A spool holder of the character described, comprising a substantially U-shaped supporting clamp, a plurality of upwardly diverging spool supporting resilient rods mounted on the clamp, outwardly turned hook portions on the upper ends of the rod, and a slidable ring encircling said rod and adapted to move the free ends thereof toward each other when said ring is moved upwardly thereon.

In testimony whereof I affix my signature.

ELSIE CATLETT.
